HAIR WAVING APPLIANCE

Bernhard M. Beskow, Miami Beach, Fla.

Application June 15, 1934, Serial No. 730,817

16 Claims. (Cl. 132—41)

This invention relates to devices or appliances for the waving of hair.

Customarily hair is waved by the simple process of dampening, curving or waving the hair while damp to the desired degree, and maintaining the hair in this curved or waved condition until dry. For holding the hair in curved or waved condition during the drying process, many appliances have heretofore been designed or suggested whereby it is made possible to place the desired curvature in one's hair without expert assistance. For one reason or another, however, appliances of this nature have seldom made their appearance on the market, and those which have have not been generally accepted. It is essential, of course, that the appliance be of light weight since in the usual case a number of them are applied to the hair during the waving operation. It is more essential still that the appliance be of such nature that it may be readily inserted into the hair and as readily withdrawn without entanglement. Again, it is highly desirable that the appliance be simple in its nature, easily manipulated, and low in cost.

The present invention contemplates a hair waving device or appliance which combines the advantages of light weight, low cost, and simplicity of operation and which also is of such nature that it may be readily inserted into the hair or removed therefrom at the completion of the waving operation with no danger of entanglement of the hair. The improved hair waving appliance is also attractive in appearance.

In certain aspects the invention is not limited to appliances for the waving of hair but has other fields of usefulness. Thus it may be employed for attaching to the hair ornamental objects, such for instance as barrettes, in which case it serves simply as an attaching clasp, the principal object of which is that it may be so freely introduced into and withdrawn from the hair, without becoming entangled, that it is superior to devices of this general nature which have been heretofore designed or placed in use.

The invention may have various embodiments, and in the accompanying drawings several such embodiments are set forth by way of example. It will be appreciated by those skilled in the art, of course, that the design and arrangement of the component elements of the invention may be considerably modified in adapting the same to its several uses.

In the drawings:

Figure 1 is a longitudinal section through one form of the appliance, certain of the relatively

movable parts being indicated in each of two positions by means of full and dotted lines;

Figure 2 is a top plan view of the same;

Figures 3, 4, and 5 are sections on the lines 3—3, 4—4, and 5—5 of Figure 1;

Figure 6 is a longitudinal section through a somewhat modified form of the appliance;

Figure 7 is a top plan view of a portion of this last mentioned form;

Figure 8 is a longitudinal section through a still further modified form of the appliance;

Figure 9 is a similar section through a further modification;

Figure 10 is a top plan view of the device illustrated in Figure 9;

Figures 11 and 12 are sections taken on the lines 11—11 and 12—12 of Figure 9, one of the relatively movable parts being indicated in two positions of Figure 11 by means of full dotted lines; and

Figure 13 is a partial longitudinal section through a still further modified form of the invention.

In a broad sense the invention may be said to comprise two hair confining means between which hair to be waved may be freely inserted, such means being interconnected, preferably having corresponding ends pivotally connected together, and one of said means including an element which may be manipulated to lock the members together and which also functions in the curving of the hair which has been inserted between the hair confining means. Preferably the element just referred to is flexible and resilient either wholly or in part and

in itself comprises an elongated member having a fixed end and a free end, the element being caused to function as a locking means when subjected to pressure longitudinally thereof against its free end, thus causing it to be distorted from its normal position. The device is thus seen to comprise three principal parts, two of which may be relatively rigid and the third flexible, preferably resilient or spring-like.

In the form of the invention shown in the first five figures of the drawings, the hair confining means are indicated generally at A and B, respectively. The means A is hereinafter designated the inner hair confining means by reason of the fact that when the appliance is in use, it lies closest to the scalp of the wearer, and the means B is hereinafter designated the outer hair confining means, lying, as it does, furthest away from the scalp. The means

A in the embodiment illustrated includes the elongated, longitudinally curved, transversely flat, and, for the purpose of strengthening, longitudinally grooved member 10 which may be 5 fabricated of thin sheet metal like aluminum or of light smooth material, such as celluloid, bone, or the like, together with the flexible element 11 which is preferably a flat, light-weight, resilient, metallic or celluloid member or spring, 10 one end of which is fixed to member 10 and preferably passes through an aperture 12 formed in this member adjacent its forward or pointed end 13, the end of member 11 being provided with a cylindrical eyelet through which the 15 transversely extending pivot 14 extends, the ends of this pivot member being secured to member 10 on opposite sides of the aperture 12. From pivot 14 the element 11 extends rearwardly, normally lying in constant close relationship to 20 the member 10, and at its extreme rear end the member 11 is provided with integral upstanding flanges 15. Flanges 15 are pivotally connected by means of pivots 16 to flanges 17 formed at the outer end of a pivoted lever 18. 25 The lever 18 is substantially rectangular and embodies at its inner corners the flanges 19, which flanges are pivotally connected by means of pivot pins 20 to the upstanding flanges 21 located at the rear corners of member 10. The 30 lever 18 is adapted to be manually moved from the position in which it is shown in full lines in Figure 1 to the position in which it is shown in dotted lines in this figure, thus shortening the linear distance between the ends of member 11 and causing it to be deflected upwardly or away from member 10.

The upper or outer hair confining means B comprises a single member which is designated 22, this member being substantially coextensive 40 in length with lower or inner member 10 and having at its rear end parallel projecting arms 23, the ends of which are pivotally connected to member 10 through pivots 20 previously referred to. The space between the parallel and rearwardly projecting arms 23 permits forward movement of the lever 18 from the position in which it is shown in full lines in Figure 1 to the position in which it is shown in dotted lines. From this point forward, member 22 is formed 45 as an inverted trough, as is clear from an inspection of Figures 3 and 4, with a transversely flat and longitudinally curved central portion 24 and downwardly and outwardly extending flanges 25. The forward end of member 22 is adapted to contact with member 10 just in front of the point of 50 pivotal connection of element 11 to member 10, the flat central portion 24 of this member being curved sharply downwardly and inwardly, as clearly shown in Figure 1, and the extreme end 55 of this part 24 comprising a catch which cooperates with the element 11 in locking the members 10 and 22 together in a manner to be hereinafter more fully described.

When the device is to be applied to the hair 60 of a person for the purpose of waving the same, the upper member 22 is elevated to its dotted-line position (Figure 1) and the appliance as an entirety thrust into the hair in a direction transverse to the strands so that a considerable body 65 of hair is confined between the means A, comprising member 10 and element 11, and the means B. In inserting the means A into the hair, the point 13 is moved under the strands which it is desired to wave, and these strands pass over the 70 point and over the upper surface of the flexible 75

element 11, this element offering no resistance and not tending to entangle the hair by reason of the fact that its forward or leading edge is depressed below the upper surface of member 10. The member 22 is then moved downwardly and the hair slightly curved, passing as it does over the upper surface of element 11 and beneath the lower edges of depending flanges 25 of member 22. The operator next swings operating lever 18 through 180° about its pivotal axis or, in other words, from its full to its dotted-line position (Figure 1). The effect of this is to raise element 11 relatively to member 22 from its full-line position (Figure 4) to its dotted-line position, thus raising the strands of hair which lie across the top of element 11 and causing these strands to be closely engaged between the upper surface of element 11 and the lower surface of parts 24 of member 22, the portions of the strands through either side of member 11 closely following the 20 contour of flanges 25.

As may be seen from Figure 1, the flexible element 11, with the exception of a short portion thereof adjacent the lever 18, lies closely against part 24 of member 22 throughout its entire 25 length. That portion of the element which is next adjacent the pivot pin 14 is curved sharply as shown and, when it reaches final position, is disposed at an acute angle to the upper surface of member 10 at this point, constituting a latch 30 and the forward sharply curved end of member 22 comprising a catch so that this member is positively locked to the member 10 as long as the flexible element is maintained in the position in which it is shown in dotted lines. That end of the element 11 which is connected to lever 18 may 35 be designated the free end of the same, and the portion of element 11 adjacent the point of pivotal connection to lever 18 is so formed and designed as to exert a downward pressure upon the lever when the lever is moved to its dotted-line position, thus tending to maintain the lever in this position and hence to lock members 10 and 22 together and maintain the strands of hair intermediate these members, as shown in dotted lines 40 in Figure 4. The two members 10 and 22 can be readily unlocked, however, and the hair released by the operator, who will simply pull back lever 18 until element 11 again occupies the position in which it is shown in full lines in Figure 1, whereupon member 22 may be raised and the entire 45 device withdrawn.

Members 10 and 22 are preferably substantially rigid and may advantageously be formed of celluloid, aluminum, or some similar light, strong, and ornamental composition. Member 11 is preferably a light steel spring but in certain instances may also be made of other resilient material. Both members 10 and 22 and element 11 are preferably perforated as shown to permit 55 the passage of air in order to facilitate drying 60 of the hair clasped within the appliance.

In the form of the invention shown in Figures 6 and 7, the outer and inner members 30 and 31 may be formed substantially in the manner described in connection with the form of the invention shown in Figures 1-5, but in this instance the rear end of member 30 is provided with a transverse cylindrical eyelet for the reception 65 of the transversely extending pin 32, the ends of which are supported in parallel upstanding flanges 33 integral with member 31. Members 30 and 31 may be swung freely relatively to each other around the axis of pivot 32. The element 34 is again an elongated flexible spring-like 70 75

member which is turned upon itself at the end in order to provide a handle portion 35 and an upward protuberance 36 just forward of the handle which is intended to act as a latch cooperating 5 with the cylindrical sleeve-like end portion of member 30 which encloses the pivot 32 in locking the element in its dotted-line position.

It will be understood that, as was the case with the first form of the invention described, 10 when the element 34 has been moved from its full-line position to its dotted-line position, the strands of hair intermediate members 30 and 31 are raised and curved. Element 34 is moved from one position to another by pushing or pulling 15 upon the handle 35 longitudinally of the appliance. The free end of the element is so formed that the portion 31 thereof normally presses against the upper surface 31 to assist in the locking of the element in its uppermost or deflected 20 position. The form of the invention just described is somewhat simpler than that illustrated in Figures 1-5, having no swinging lever to which the movable end of the element is connected.

As shown in Figure 8, it is not essential that 25 the hair strand deflecting element be uniform throughout its length or that all portions of it be resilient. For instance, as shown in Figure 8, its central portion 40 may be comparatively 30 rigid and only its end portions 41 and 42 of flexible and resilient material. When the element is upwardly flexed by pressure applied upon its free end, both its forward and rearward resilient ends will be flexed, as indicated in dotted lines 35 in Figure 8, but the intermediate portion 40 will simply engage a correspondingly curved part of the outer hair confining member 43.

However, in this form of the invention as in 40 the two embodiments first described, it is necessary that the outer hair confining means constitute a continuous limiting stop or guide for the flexible element which, due to the manner in which it is constructed, would not move into any definite predetermined final position when laterally expanded or deflected, except when some 45 guide means is present. It is possible, however, to dispense with the positive guide for the flexible element, that is, to dispense with the trough-like hair confining member such as indicated at 43 in Figure 8 if the various parts of the invention 50 are arranged as shown in Figures 9, 10, 11, and 12. In the form of the invention shown in these figures, the inner hair confining means 44 includes the longitudinally curved and transversely 55 flat elongated member 45, which is generally similar to the inner members heretofore described in connection with the other embodiments of the invention, and the flexible element 46 having an intermediate portion which is substantially inflexible and end portions which are flexible.

Preferably member 46 is formed as a continuous element having a thickened central part and end portions sufficiently thin to allow them to flex from the position shown in full lines in Figure 9 to the dotted-line position in this figure. The upper hair confining member 47 is formed 65 as an elongated U-shaped wire member, the ends being provided with eyelets encircling the pivot 48 so that member 47 is pivotally connected to the lower member 45 for swinging movement about the axis of pivot 48. The numeral 49 represents a spacing element or sleeve which encircles pivot 48 and also acts as a catch 70 which cooperates with the raised locking portion

50 formed in that end of the element 46 adjacent the operating handle 51.

In this modified form of the invention, the member 47 is elevated as usual (Figure 9). The member 45 and the substantially inflexible element 46, which together normally constitute a united, practically unobstructed, flat and thin surface, are inserted in the hair, and the member 47 is then depressed as shown by Figures 9, 10, and 11. Thereafter longitudinal pressure is applied to the handle 51 and element 46 caused by this pressure to assume the position in which it is shown in dotted lines in Figure 9, the forward end of the element engaging the forward transversely extending portion of the wire member 47 and locking it in this position, and the raised portion 50 engaging the sleeve 49 and preventing accidental movement of the element 46 to its original position. After the hair is dry, the device is easily unlocked by a slight pull on 20 the handle 51, and the hair strands are completely released by lifting the U-shaped wire member 47.

In all forms of the invention the various parts are so designed and put together as to permit 25 speedy application of the device to the hair and without danger of entanglement. While I have illustrated and described certain advantageous 30 embodiments of the invention, further modified forms are contemplated in adapting the same for imparting various curvatures to the hair in 35 waving operations. Likewise, in adapting the principles of the invention to appliances which are not primarily intended for waving but, on the other hand, are intended for securing barrettes, etc., the various component elements of 40 the invention may be considerably modified in 45 dimension and arrangement.

In Figure 13 is shown in section a modified 45 form of the hair waver in which the flexible element 60 is provided upon its upper surface and at one end with corrugations or protuberances or is roughened, and in which a laterally extending roller of hard rubber or other suitable material 61 is provided to engage this surface and lock the flexible element in any one of a number of positions to make the wave in the hair higher or lower as desired. The ends of roller 61 are positioned in inclined slots 62 formed in parallel flanges 63. By pressing down on the 50 roller it may be caused to firmly grip the element 60 and to hold it against movement, a slight pressure upwardly upon the roller resulting in its disengagement.

Having thus described the invention, what is 55 claimed as new and desired to be secured by Letters Patent is:

1. A hair waving appliance comprising elongated inner and outer hair confining means between which hair to be waved may be freely 60 inserted, one of said means having an element shiftable toward the other means to cause hair so inserted and confined to be closely engaged between said element and said other means.

2. A hair waving appliance comprising elongated inner and outer hair confining means between which hair to be waved may be freely 65 inserted and confined, one of said means being expansible laterally toward the other means to cause hair so inserted to be closely engaged between said inner and outer means.

3. A hair waving appliance comprising elongated inner and outer hair confining means between which hair to be waved may be freely 70 inserted, one of said means including an elong- 75

- gated resilient element adapted to be laterally distorted toward the other means when subjected to longitudinal pressure.
4. A hair waving appliance comprising elongated inner and outer hair confining means between which hair to be waved may be freely inserted, one of said means including an elongated flexible element having one end fixed and the other end free, said element being adapted to be laterally distorted toward the other means when longitudinal pressure is applied to the free end to cause hair positioned between said means to be closely engaged between said element and one of said means.
15. 5. A hair waving appliance comprising two comparatively inflexible elongated hair confining members, between which hair to be waved may be freely inserted, and a flexible element intermediate said members, said element having one end secured to one of said members and normally lying lengthwise of and closely adjacent said member, the other end of said element being free to move longitudinally of said member toward the secured end of the element, whereby the intermediate portion of the element is moved toward the other member to cause hair positioned between said members to be closely engaged between said element and said other means.
20. 6. The combination set forth in claim 5 in which the appliance includes means for locking the said element in hair engaging position.
7. The combination set forth in claim 5 in which the element has means adjacent its free end for engaging one of said members and locking said element in hair engaging position.
35. 8. In a hair waving appliance, in combination, two elongated hair confining members pivotally connected together, an elongated flexible element intermediate said members and having one end thereof attached to one of said members, and means for applying pressure to the free end of the element to cause its intermediate portion to be deflected into close proximity to the other element.
40. 9. The combination set forth in claim 8 in which said element comprises a locking device for locking said members together when in its deflected position.
45. 10. The combination set forth in claim 8 in which said pressure applying means comprises a lever having one end pivotally connected to one of said members and its other end pivotally connected to one end of the element.
50. 55. 11. A hair waving appliance comprising two elongated members, between which hair may be loosely confined, and a single element movable relatively to both of said members for locking said members together and simultaneously
- pressing the confined hair against one of said members.
12. A hair waving appliance comprising two elongated members between which hair may be loosely confined, adjacent ends of said members being pivotally connected together and the opposite end of one member having a catch, and a flexible element having one end connected to the other member and adapted to be manually deflected so as to lockingly engage said catch and thereby lock said members together.
13. An appliance of the type described comprising two relatively movable elongated means between which hair to be waved may be freely inserted, which hair is curved when said means are moved laterally relatively to each other into predetermined relationship, said means having mutually interlocking portions and being locked together in such predetermined relationship by relative longitudinal movement in one direction and thereafter unlocked by relative longitudinal movement in the opposite direction.
15. 14. An appliance of the type described comprising two elongated members having corresponding ends hingedly connected together and between which hair to be waved may be freely inserted, and a flexible element secured to one of said members, said element being movable longitudinally of the member upon which it is mounted into locking engagement with the other member when said members are in hair waving position.
20. 15. An appliance of the type described comprising two elongated members having corresponding ends hingedly connected together and between which hair to be waved may be freely inserted, and an element having one end fixed to one of said members and its other end movable longitudinally of said member, said element having a flexible portion adjacent its fixed end, pressure upon the movable end of the element resulting in flexing of said flexible portion and causing said portion to interlock with that member to which it is not fixed.
25. 16. An appliance of the class described comprising, in combination, two elongated relatively rigid members, the end of one of which is pivotally connected to the corresponding end of the other, an element adapted to be transversely flexed when subjected to longitudinal pressure and having one end pivotally connected to one of said members at a point remote from said pivotal connection and its free end adjacent said pivotal connection, said other member having a portion adapted to be engaged by said element when the element is flexed, due to the application of longitudinal pressure upon its free end, whereby the said members are locked together.
30. 35. 40. 45. 50. 55. BERNHARD M. BESKOW.
